UNITED STATES PATENT OFFICE.

ALEXANDER BERNHARD DRÄGER, OF LUBECK, GERMANY; ELFRIEDE DRÄGER, NÉE STANGE, EXECUTRIX OF SAID DRÄGER, DECEASED.

SELF-CONTAINED BREATHING APPARATUS.

Application filed October 29, 1925, Serial No. 65,693, and in Germany September 5, 1925.

Breathing apparatus consisting of an air purifying cartridge, in combination with a breathing tube and bag and an oxygen container in which the connection of the aforementioned parts is effected by means of a connecting-piece provided with controlling means for the oxygen supply, are already known. This connecting-piece is fastened, by means of a support or a foot, as the case may be, to a carrier plate, whereby the breathing apparatus may be carried on the body. The controlling means comprise a pressure reducing valve, a manometer or high pressure gauge, and a manually operated auxiliary valve for passing extra oxygen. The auxiliary valve may conveniently be constructed as a press-button valve.

In these known breathing apparatus, however, the three oxygen controlling means (pressure reducing valve, high pressure gauge and auxiliary valve) are arranged in quite an unsuitable manner on the multiway connecting-piece. In particular, no account has been taken therein of the fact that the high pressure gauge must be so disposed that it can be comfortably observed by the wearer of the apparatus. Furthermore no care has been taken to mount the auxiliary valve in a sheltered position and yet so that it can be easily and comfortably found and actuated by the hand or by a finger, and, finally, no attention has been given to locating the pressure reducing valve in a place where it is least in the way and yet is protected. Furthermore, the rigid connection of the multiway connecting-piece to the carrier plate frequently militates against satisfactory self-adjustment and seating of the seating surfaces of the screw connections and impairs the interchangeability of cartridge and oxygen bottle.

The present invention remedies the troubles arising from neglect of these pre-requisite conditions, inasmuch as the connecting-piece, for the assembly and attachment of the aforementioned controlling fittings, is provided with three contact faces carrying the above mentioned three controlling fittings in the desired position. Preferably the contact face for the gauge is upwardly and outwardly directed with respect to the breast plate and the contact face for the manual valve is downwardly directed and the contact face for the automatic valve is upwardly and inwardly directed.

In relation to a circle in the plane of the

axes of the operative fittings, it may be said that the auxiliary valve lies underneath the multiway connecting-piece, the high pressure gauge separated therefrom by about 120°, points outwards, and the pressure reducing valve is directed inwards in substantially the same angular relationship.

Moreover, the connecting-piece is not rigidly connected to the carrier plate, but is so fastened thereto that it may be angularly adjusted about an axis approximately perpendicular to the plane of the carrier plate.

This arrangement of the controlling fittings and of the adjustable support has the following advantages: The operator can comfortably observe the scale of the high pressure gauge, without having to strain the head or even the whole trunk forward, as was necessary with the usual arrangements hitherto in use. With the new apparatus, the operator has only to lower his gaze with a slight inclination of the head when he wishes to ascertain the momentary position of the high pressure gauge pointer on the scale. The auxiliary valve is not visible for the wearer but lies sheltered underneath the high pressure gauge, for example, under the connecting-piece, hence it is protected from outside influences but can, nevertheless, be found and actuated easily and comfortably by the hand or by the finger. The free space on the inner side of the connecting-piece, between the latter and the carrier plate, in the angle between the auxiliary valve and the high pressure gauge is particularly well adapted for the housing of the pressure reducing valve, since in this place it is least hindering and is also protected.

A constructional embodiment of the invention is shown in the drawing. Figure 1 shows the breathing apparatus in elevation. Figure 2 is an elevation of the connecting-piece, drawn to an enlarged scale and looked at from a line of section A—B in Figure 1. Figure 3 is a section on the line C—D of Figure 2; Figure 4 is a section on the line E—F of Figure 2; Figure 5 shows the support of the connecting-piece separately and to an enlarged scale; and Figure 6 is a section on the line G—H of Figure 5.

The end of the connecting piece *d* containing the low pressure channel *d*¹, is connected to the air purifying cartridge *a* and the breathing bag *c*, by means of screw connections *a*¹ and *c*¹ respectively; the other end

provided with the high pressure channel d^2 , is connected by a union nut b^1 to the oxygen bottle f . The high pressure channel d^2 and the low pressure channel d^1 lie co-axially but 5 are not in direct communication with each other. The connecting-piece is suitably fastened to a carrier plate e , for instance, by means of a cranked support g , which, by means of a bearing or socket g^1 is mounted on a pivot 10 pin e^1 fastened to the plate e . The range of angular adjustability of the support g about the pin e^1 is limited by a screw g^2 which is screwed through the wall of the socket g^1 and engages a recess in the pin e^1 , thus acting as 15 a stop. The angle of adjustability of the support g (shown in Figure 5) is dependent upon the length of the recess. By reason of the possibility of adjusting the connecting-piece, which is suspended from the pin g^3 of the 20 support g by means of an eye d^3 , the seatings of the connections of the valve casing of the oxygen bottle, of the cartridge and of the breathing bag, as well as those of the connecting-piece may be brought into proper ad- 25 justment more easily and better.

About midway of the length of the connecting-piece d , where high and low pressure passages are separated from each other by solid material, the said connecting-piece is 30 provided at its circumference with three branch projections h , i , k which, as shown in Figure 2, are distributed around the connecting-piece at suitable angles to one another and with their axes in a plane at right angles to 35 the longitudinal axis of said connecting-piece. Thus the connecting-piece and the branch projections may be designed, in a very simple manner as a cast or pressed unit. On the contact face of the branch h , which inclines 40 outwards and upwards with respect to the carrier plate (Figure 2), a high pressure gauge m is fitted. The downwardly pointing branch projection i , carries a press-button valve n and on the inwardly and upwardly pointing branch k , a pressure reducing 45 valve o is fixed. The high pressure gauge m , the press-button valve n and the pressure reducing valve o are connected to the high pressure channel d^2 , respectively, through branch 50 passages p , q and r formed in the casting. Moreover, from the press-button valve n and the pressure reducing valve o suitably disposed passages s and t branch off respectively to the low pressure channel d^1 .

55 The arrangement and function of the high pressure gauge, of the press-button valve and of the pressure reducing valve, as well as

the whole apparatus, are known and therefore require no further explanation.

1 claim:

1. In a breathing apparatus including a vertical carrier plate, an air purifying cartridge and an oxygen container, the combination of a connecting-pipe rigidly attached to the carrier plate and extending between, and supporting the cartridge and the container, said connecting-pipe being provided with two axial opposite channels, one of which communicates with the oxygen container and the other leading to the cartridge, three lateral 70 contact faces on said connecting-pipe, an automatic pressure reducing valve fixed upon one of said contact faces, a manually controlled auxiliary valve carried by another of said faces, and a pressure gauge mounted 75 upon the third of said faces, said contact faces being circumferentially disposed on said connecting-pipe in such a manner that the contact face for the gauge is upwardly and outwardly directed with respect to the 80 carrier plate and that the contact face for the manual valve is downwardly directed and that the contact face for the automatic valve is upwardly and inwardly directed, the connecting-pipe being furthermore provided 85 with radial branch-passages leading from the aforementioned axial channels to openings in the respective contact faces.

2. In a breathing apparatus including an air purifying cartridge and an oxygen container, the combination comprising a connecting pipe extending between, and rigidly connecting, the cartridge and the container, and provided with an axial channel leading 90 to said cartridge, and with another axial 95 channel opposite to the first and leading to said container, an automatic reduction valve, a manual valve, and a pressure gauge laterally mounted on said pipe, the manual valve being arranged beneath the longitudinal axis 100 of the connecting pipe so as to be operated by an upwardly directed movement of the hand, the gauge being arranged above the pipe and outwardly inclined with respect to the carrier plate so as to be easily observed 105 by the operator, and the automatic valve being arranged in the space between the carrier plate and the pipe in a protected position.

3. The improvement in a breathing apparatus set forth in claim 2, in which the automatic reduction valve, the manual valve, and the pressure gauge are positioned at angles of about 120° with respect to each other.

Dr. ing. h. c. ALEXANDER BERNHARD DRÄGER.
